UNITED STATES PATENT OFFICE.

NORMAN E. WOODS, OF RICHMOND, VIRGINIA.

VALVE.

1,156,963.

Specification of Letters Patent.

Patented Oct. 19, 1915.

Application filed April 20, 1914. Serial No. 833,171.

To all whom it may concern:

Be it known that I, NORMAN E. Woods, a citizen of the United States, residing at Richmond, in the county of Henrico and State of Virginia, have invented a new and useful Valve, of which the following is a specification.

This invention relates to an improvement in valves, the objects being to provide a valve designed for use in connection with any fluid, as for example, air, gas, water, steam, &c., and so constructed as to thoroughly and effectually strain the same and free it from all foreign matter, and to adapt said valve to be self cleansing and capable of discharging such foreign matter collected therein to one side and out of the course of said liquid.

Other minor objects of the invention will hereinafter appear and the novel features of the invention will be specifically pointed out in the appended claims.

Referring to the drawings: Figure 1 is a central vertical longitudinal sectional view of a valve embodying my invention, the valve being open. Fig. 2 is a central horizontal longitudinal sectional view of the same, the parts being in the same position. Fig. 3 is a view similar to Fig. 2, the valve being in the act of self-cleansing. Fig. 4 is also a view similar to Fig. 2, the valve being closed or in its cut-off position. Fig. 5 is a portion of the valve in plan, the wall of the valve being broken away. Fig. 6 are details in bottom plan and side elevation of the toothed washer. Fig. 7 is a detail in plan of the valve operating lever or handle.

Similar numerals of reference indicate similar parts in all the figures of the drawings.

The valve-casing or shell 5, may have any external appearance or design desired and best adapting it for the purpose intended. At its opposite longitudinal ends it is provided with inlet and outlet-openings or passages, 6 and 7, respectively, the same being suitably threaded and designed to form proper connections with the usual supply and discharge. The casing or shell is furthermore provided with a vertically disposed transverse bore 8, tapered slightly from its lower end upwardly and extending through and through the casing. The lower end of this bore is internally threaded and is closed by a removable plug-cap 9. The upper side of this cap is provided with a

chamber 10, and the underside with an external wrench-receiving projection or surface 11. Neatly fitted within the tapered bore 8 of the valve-casing or shell and capable of rotating therein, is a correspondingly tapered valve-plug 12. This plug terminates at its lower end a slight distance above the plug-cap 9 and at its upper end above the valve-casing or shell, at which point it is squared, as at 17, to receive the socket-head 13 of the operating handle or lever 14, a pin being preferably used to connect these parts removably together. The upper surface of the valve-casing or shell, immediately surrounding the valve-plug, is provided with a series of inclined ratchet-teeth 16, in this instance, six in number, the same being designed to be successively engaged by a tooth 15, depending from a washer 21, encircling, mounted upon, and moving with the valve-plug and operating-handle. By this means, it will be apparent that the valve-plug can only be rotated in one direction, the object of which will be hereinafter apparent. The valve-plug, as is usual, is provided with the transverse ports 22 and 23, the same being elongated and each capable of being alined with each of the ports or passages 6 and 7 of the valve-casing. In addition to these transverse ports 22 and 23, the valve-plug is formed with an upwardly disposed bore 24 enlarged and open at its lower end, as at 25, and at its upper end forming a seat 26^b, the aforesaid bore intersecting at right angle the ports 22 and 23. The diameter of this bore is but very slightly greater than the width of the ports 22 and 23. A removable plug, 26, closes the lower end of the bore 24, the plug having an enlargement or flange 27 at its lower end designed to fit in the enlarged opening 25 of the bore of the valve-plug. Seated within the chamber 10 of the plug-cap 9 and bearing upwardly against the flange 27 of the plug 26, so as to retain the latter in position, is a coiled spring 28. A cylindrical strainer of proper mesh, and indicated as 29, is seated over the plug 26, extends upwardly through the bore 24 of the valve-plug and terminates in the seat 26^b. The lower end of this strainer may be flared, as indicated at 29^a, to fit over the flange 27 of the plug 26, and be clamped by said flange and the lower end of the valve-plug. This flange of the strainer may be left disconnected from the plug, or as shown, pinned

thereto, the object being to cause the strainer to move with the valve-plug, all as will hereinafter appear. The strainer is of a diameter very slightly smaller than the bore 5 of the valve-plug in which it fits, so that it completely fills the same and effectually covers the inner ends of the ports 22 and 23 of the valve-plug so as to prevent foreign matter passing beyond the port and entering the 10 plug. At an angle to the longitudinally disposed inlet and outlet-openings 6 and 7 of the valve-casing, the latter is provided at one side with a discharge port or opening 29^b, communicating at its inner end with 15 the bore of said valve-casing and therefore being in line with the ports thereof and those of the valve-plug. A curved passage 30, communicates with the bore of the valve-casing at a point diametrically opposite the 20 point of communication of the discharge-port or opening 29^b, and extends rearwardly and communicates at its other end with the inlet-port 6 of the valve-casing.

This completes the construction of the 25 improved valve and the operation thereof may be briefly stated as follows: Taking the parts in the positions shown in Figs. 1 and 2, it will be seen that any liquid entering the inlet-passage or port 6, will pass 30 through the ports 22 and 23 of the valve-plug and also through the strainer 29, and thence out through the discharge-port 7 of the valve. By passing through the strainer the liquid will be freed from all foreign 35 matter, and the latter will collect at the back of the strainer in the port 23 of the valve-plug. Now by operating the handle 14 the distance of one tooth of the ratchet 16, the valve-plug and its strainer will be 40 partially rotated, the parts being thereby brought to the position shown in Fig. 3. When this occurs, it will be seen that the port 23 of the valve-plug will be in line and communication with the discharge-outlet 29^b 45 and the port 22 of the valve-plug in line and communication with the side port 30, the inlet and outlet-ports of the valve proper being closed. In this manner a discharge of the liquid is directed through the side-port 50 30, the ports 22 and 23 and the discharge port 29^b, the foreign matter lying within the port 23 being blown or discharged out the port 29^b. A further movement of the operating handle and the valve-plug the distance of one tooth will bring the parts to the 55 position shown in Fig. 4, wherein all the ports are closed. Again, by the further movement of the handle the distance of a tooth, the valve is opened, as in Fig. 2. In 60 this manner, each time that the valve is closed after use, the strainer is cleansed of all foreign matter before the closing opera-

tion can take place and before the valve can again be opened, and when opened a cleaned side of the strainer is always presented to 65 the discharge side of the casing. Strainers may be removed and new strainers inserted when occasion requires simply by removing the plug-cap 9 and withdrawing the strainer and its supporting plug. It will be noted 70 that the exhaust or clearance-port 29^b is disposed at an angle rearward, such being the result of the presence of an extended lip or guard 29^c. By this arrangement the strainer is guarded against puncture or 75 injury when the valve-plug is turned so as to discharge through the said port 29^b.

Having described my invention, what I claim is:

1. A valve of the character described comprising a casing having inlet, outlet and exhaust ports, a manually operable rotary plug valve in said casing provided with a central longitudinal passage for coöperation with 80 said ports, a screen fitted in said passage so as to provide pockets on opposite sides of the valve and screen, and means for permitting rotation of the valve in one direction and holding the valve against rotation in 85 the opposite direction.

2. A valve of the character described comprising a casing having inlet, outlet and exhaust ports, a manually operable rotary plug valve in said casing provided with a central longitudinal passage for coöperation with 90 said ports, a circular screen fitted in said passage concentric with the axis of the valve so as to provide pockets on opposite sides of the valve and screen, and means for permitting rotation of the valve in one direction and holding the valve against rotation in 95 the opposite direction.

3. In a valve of the character described comprising a casing having inlet, outlet and exhaust ports, a manually operable rotary plug valve in said casing provided with a central longitudinal passage for coöperation with 100 said ports, a screen fitted in said passage so as to provide pockets on opposite sides of the valve and screen, and means for permitting rotation of the valve in one direction and holding the valve against rotation in 105 the opposite direction, the said exhaust port being provided with a guard portion rendering said port of angular form so as to prevent the introduction of an implement whereby the screen may be perforated.

In testimony whereof, I have signed my name to this specification in the presence of two subscribing witnesses.
